UNITED STATES PATENT OFFICE

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

REFINING OF PETROLEUM OILS

No Drawing.

Application filed December 9, 1925. Serial No. 74,384.

This invention relates to improvements in refining of petroleum oils, and refers more particularly to the subjection of the lighter gravity overhead products of petroleum cracking and distillation to treatment with refining agents, for the purpose of removing or converting color-forming, odor-forming sulphur and other objectionable compounds which detract from the commercial value of the product.

The essence of the present invention resides in the treatment of such gasoline-like bodies to produce substantially water-white odorless products suitable for commercial use.

As a specific embodiment of the present invention, the petroleum oil is subjected to the action essentially of acid sulphates in solution such as ammonium hydrogen sulphate, sodium hydrogen sulphate, and other soluble hydrogen sulphates to remove all or a portion of the objectionable compounds.

It is well known that the action of concentrated sulphuric acid upon some types of oil, particularly upon what is known as cracked distillate, may be such that while the concentrated sulphuric acid exerts a refining effect in removing undesirable substances, it may also react at the same time with some of the undesirable substances present in the cracked distillate in such manner that its refining action in part is neutralized. For this reason it has been found desirable in certain instances to subject such oil previous to the application of sulphuric acid, to the action of the acid salts of sulphuric acid for the purpose of removing those substances which as described above, when acted upon subsequently with concentrated sulphuric acid, produce undesirable compounds remaining in the oil, causing the partially refined oil to become unstable with respect to color and odor.

It has been found that this treatment with the acid salts of sulphuric acid or acid sulphates in aqueous solution, has a softening or ameliorating effect upon the subsequent treatment with concentrated sulphuric acid. By the term acid sulphate it is of course, understood that I refer to the acid salts of sul-

phuric acid which contain hydrogen in their composition.

The acid sulphates may be used as refining agents in combination with concentrated sulphuric acid, or the acid sulphates may be used in any combination with any of the well known refining agents now utilized such as alkali, plumbite (litharge dissolved in sodium hydroxide), copper salts, earthy adsorbents and the like. I do not of course, wish to limit myself to any particular order or succession of treatment as the refining agents may be used in any order which will produce the most satisfactory results, to be determined by the skilled operator. The oil may be subjected to water washing subsequent to being subjected to the action of the various refining agents described.

To determine the advisability of subjecting the oil to the action of other refining agents, the skilled operator will carry out tests for the purpose of determining this factor based upon the character of the oil being treated, and the commercial requirements.

The above refining treatment is particularly adapted to the treatment of lighter gravity products of petroleum distillation or cracking, which requires no further distillation such for instance, as those products having an end boiling point conforming to commercial requirements, and which are produced directly from the cracking process, although of course, the refining treatment is not limited to that particular field, but includes the treating of any overhead products which require treatment.

I claim as my invention:

1. A step in a process for refining the lighter gravity liquid products obtained from the distillation or cracking of petroleum oils, comprising subjecting said lighter gravity liquid products to the action of an acid sulphate in aqueous solution.

2. Steps in a process for refining the lighter gravity liquid products obtained from the cracking of petroleum oils, comprising separately subjecting said lighter gravity liquid products to the action of an acid sulphate in aqueous solution, and sulphuric acid.

3. Steps in a process for refining the lighter gravity liquid products obtained from the cracking of petroleum oils, comprising separately subjecting said lighter gravity liquid products to the action of copper salt in aqueous solution, and an acid sulphate in aqueous solution.

4. Steps in a process for refining the lighter gravity liquid products obtained from the cracking of petroleum oils, comprising separately subjecting said lighter gravity liquid products to the action of copper salt in aqueous solution, an acid sulphate aqueous in solution and sulphuric acid.
